UNITED STATES PATENT OFFICE.

HARRY PAYTON, OF PROVIDENCE, RHODE ISLAND.

CHAIN.

Application filed February 12, 1925. Serial No. 8,696.

To all whom it may concern:

Be it known that I, HARRY PAYTON, a citizen of the United States, residing at Providence, in the county of Providence and State of Rhode Island, have invented 5 certain new and useful Improvements in Chains, of which the following is a specification.

This invention relates to an improved 10 construction of chain or bracelet; and has for its object to provide a bracelet comprising a series of sheet metal, hollow, box-shaped links loosely connected by loop-shaped links.

15 A further object of the invention is to form the box-shaped links of sheet metal having side and end walls with extending portions, which portions are folded inwardly to form a bottom wall for the box, the adjacent walls of the adjacent box links 20 in the chain are provided with slots through which the loop link extends to loosely connect these walls of these links together.

With these and other objects in view, the 25 invention consists of certain novel features of construction, as will be more fully described, and particularly pointed out in the appended claims.

In the accompanying drawings:

30 Figure 1 is a side elevation of my improved bracelet or chain showing its ends connected together.

Figure 2 is a perspective view of a blank 35 cut from sheet stock adapted to be folded into box-shape form from which the links of the chain are formed.

Figure 3 shows this blank as folded into box-shape and showing the extending end portions of both the side and end walls before they are folded inwardly toward each other to form the bottom of the box.

Figure 4 is a perspective view showing a loop-shaped link for loosely connecting together the box links of the chain.

45 Figure 5 shows these loop links as positioned on a partly folded box link, the extending wall ends of the link extending through the loop and ready to be folded inwardly thereover.

50 Figure 6 is a perspective view showing both the end and side walls of the box link as folded inwardly to form the bottom of the box link also showing one of the loop links as engaged by the wall of the box link.

Figure 7 is a bottom view showing a 55 series of box links as connected together by loop links.

Figure 8 is a top view showing a series of box links as connected together by loop 60 links.

Figure 9 is a sectional edge view on line 9—9 of Figure 7, showing a series of box links as connected by a series of loop links, one of the box links being swung off at an angle to the plane of the other links. 65

Figure 10 is an enlarged sectional elevation on line 10—10 of Figure 8 through one of the box links.

It is found in the practical construction of chain or bracelet structures of this character particularly where the boxes are elongated and each to provide a setting for more than one gem, of advantage to form the connecting loop link of a width less than that of the box link so as not to extend 70 to the sides thereof, to render these connecting loop links less conspicuous and to further render these loop links less conspicuous, I have provided extensions on the side walls of the box links, and have 75 folded these extending portions inwardly toward each other to cooperate with inwardly-folded extensions on the end walls thereof, to provide a substantially closed bottom portion to the box link, which closed 80 bottom portion also serves to render the 85 bracelet much more slightly from its underside and also provides a broad and smooth bearing surface on the arm of the wearer, when used as a bracelet; and the following 90 is a detailed description of the present embodiment of my invention showing one construction by which these advantageous results may be accomplished:—

With reference to the drawings, each of 95 the box links is preferably formed of sheet stock first by being blanked out into the form illustrated in Figure 2, and then folded into the shape illustrated in Figure 3, having side walls 10 with extending portions 11 notched at their end corners as at 12, and end walls 13 having extending portions 14, said end walls being notched as at 15 to receive the connecting loop links 16.

In assembling the parts, these loop-shaped 105 links are employed for loosely connecting the adjacent end walls of the adjacent box links together, the central opening 17 in

the loop link being of a size to receive extensions 14 of the end walls of the two adjacent links with sufficient additional space to permit flexibility or relative bending or swinging movement of one link upon the other. After a series of these box links has been assembled and the loop link positioned over the extensions 14 of the end walls to connect these links together, these 10 end wall extensions are folded inwardly over these loop links to secure them in position and to assist in providing a bottom wall for closing the bottom portion of the link; then the extending end portions 11 of the 15 side walls are folded inwardly to complete the bottom wall, the notches 12 in these side wall extensions serving to cooperate with the notches 15 of the end walls to permit a tipping or hinging motion of the box links 20 one upon the other.

In this particular type of bracelet, I preferably swage inwardly the top wall of the box link to provide a plurality of conically-shaped seats 18 for the reception of the 25 gems 19 to be set therein, and have provided bendable lugs 20 raised from this top wall about the setting recess to be bent over the edges of the gems to firmly retain them in their seats.

30 My improved form of bracelet or chain structure is very simple and practical in construction, the loop links which join the box links being quite inconspicuous and can hardly be observed even when the box links 35 are swung at a sharp angle to each other and when upon the wrist of the wearer these connecting loop links are practically invisible from the edge of the chain or bracelet.

40 The foregoing description is directed solely towards the construction illustrated, but I desire it to be understood that I reserve the privilege of resorting to all the mechanical changes to which the device is susceptible, the invention being defined and limited 45 only by the terms of the appended claims.

I claim:

1. A chain structure comprising a series of 50 sheet metal box-shaped links, each having side and end walls, said walls having extending portions, a bottom wall formed by fold-

ing all of said wall extensions inwardly, said walls being of a length to meet and form a bottom wall, the end and bottom walls of adjacent links being provided with notches, 55 and a loop link engaged by said walls of adjacent links and extending through said notches to pivotally connect said box links together.

2. A bracelet chain structure comprising a 60 series of hollow box-shaped links, each formed of sheet metal having integral top, bottom and side and end walls, spaced notches in the end and bottom walls of adjacent links located inwardly from the side 65 thereof, loop links in said notches extending between adjacent box links and having a transverse dimension less than that of said box links, said end walls of adjacent box links extending through said loop links to 70 hingedly connect the box links together.

3. A chain structure comprising a series 75 of sheet metal hollow box-shaped links, each having side and end walls, said link having a bottom wall formed of meeting inwardly-folded extending portions on both of said end and side walls, both the bottom wall and adjacent end walls being notched, and loop 80 shaped links in said notches through which a portion of said end wall extends to hingedly connect the box links together.

4. A bracelet chain structure comprising a 85 series of box-shaped links, each formed of sheet metal having a top wall with a plurality of recesses therein for the reception of gems, side and end walls bent downwardly from said top wall, integral foldable extension portions on both the side and end walls, notches in said end wall, loop links 90 between adjacent box links located in said notches, each of the end walls of adjacent box links extending through a loop link and being inturned to meet and form a portion of the bottom wall of said box and the extensions on said side walls also being inturned to meet the inturned side wall portions and complete the bottom wall of said 95 box and notched to cooperate with the notched side wall and form a working space for the loop link.

In testimony whereof I affix my signature.
HARRY PAYTON.
